BILLIARD TABLE POCKET

Theodore Silverman, 230 Broadway,
Denver, Colo. 80203

Filed Aug. 13, 1970, Ser. No. 24,463

Term of patent 14 years

Int. Cl. D21—01

U.S. Cl. D34—3

Fig. 4

Fig. 5

FIG. 1 is a top plan view of a billiard table pocket embodying my new design;

FIG. 2 is a front elevation thereof;

FIG. 3 is a side elevation thereof;

FIG. 4 is a rear elevation thereof; and

FIG. 5 is a vertical section taken along line 5—5 of FIG. 1.

I claim:

The ornamental design for a billiard table pocket, as shown.
